United States Patent Office

Des. 202,469
Patented Oct. 5, 1965

202,469
CUP

Paul Davis, Beverly, Mass., assignor to Sweetheart
Plastics, Inc., Wilmington, Mass., a corporation of Maryland

Filed Aug. 3, 1964, Ser. No. 81,148

Term of patent 14 years

The portion of the term of the patent subsequent to
Sept. 15, 1978, has been disclaimed
(Cl. D44—9)

FIG. 1

FIG. 2

FIG. 1 is a side view partly in cross-section of a cup showing my new design; and

FIG. 2 is a bottom plan view thereof.

I claim:

The ornamental design for a cup, as shown.
